UNITED STATES PATENT OFFICE.

JOHN C. LYONS, OF McCOMB, MISSISSIPPI.

LOCOMOTIVE-AXLE THRUST AND REINFORCE.

1,283,441.

Specification of Letters Patent.

Patented Oct. 29, 1918.

Application filed January 25, 1918. Serial No. 213,725.

To all whom it may concern:

Be it known that I, JOHN C. LYONS, a citizen of the United States, residing at McComb, in the county of Pike and State of Mississippi, have invented certain new and useful Improvements in Locomotive-Axle Thrusts and Reinforces; and I do declare the following to be a full, clear, and exact description of the invention, such as 10 will enable others skilled in the art to which it appertains to make and use the same.

One object of the present invention is to provide a thrust bearing for locomotive axles which can be easily adjusted to take up wear 15 and which will permit an excessively worn liner to be removed and replaced more quickly and easily than when employing the arrangement now commonly used, that is the location of liners between the wheel hubs 20 and the axle boxes.

In the present invention, the liners are located between the inner sides of the axle boxes and a pair of sleeves which are removably and adjustably clamped on the axle; 25 and a further object is to provide novel means for forcing said sleeves outwardly to the proper extent for preventing movement of the boxes longitudinally upon the axle.

A still further object is to so construct 30 and arrange the aforesaid sleeves as to cause them to reinforce the axle on which they are used.

With the foregoing general objects in view, the invention resides in the novel features of construction and unique combinations of parts to be hereinafter fully described and claimed, the descriptive matter being supplemented by the accompanying drawings which form a part of this specification and in which:

Figure 1 is substantially a horizontal section showing the application of my invention to one of the axles of a locomotive; and

Figs. 2, 3 and 4 are vertical transverse sections on the planes indicated by the lines 2--2, 3--3 and 4--4 respectively of Fig. 1.

In the drawing above briefly described, the numerals 1 designate two of the drivers of a locomotive, 2 has reference to the axle 50 upon the ends of which said drivers are rigidly carried, and the numerals 3 denote the boxes of the axle, said boxes being located at the inner sides of the drivers 1 and being carried in the usual or any preferred manner by the locomotive frame 4. Here-

tofore, in order to prevent lateral shifting of the locomotive frame upon the axle, liners have commonly been employed between the outer ends of the boxes 3 and the hubs of the wheels 1, and whenever it is necessary 60 to remove one of these liners to replace a new one, a great many parts of the locomotive must be disassembled. This not only means loss of time at the shop, but additional loss since the locomotive is out of use for a 65 considerable length of time. Due to the nature of the invention described below, repairs may be much more easily and quickly made and in addition to this advantage, the 70 axle is reinforced.

A pair of sleeves 5 surround the axle 2 and extend from its center to the boxes 3, each sleeve being formed of two semi-cylindrical sections 6 having longitudinal flanges 7 on their edges which are secured together 75 by bolts 8 in order to clamp the sleeves tightly upon the axle. The outer end of each sleeve 6 is provided with a circumferential flange 9 forming a thrust bearing for cooperation with the inner end of the adjacent box 3, said flanges being likewise formed in sections, and joined integrally at their ends to the end of the flanges 7. Bracing webs 10 are also provided for the flanges 9, said webs extending from these flanges to 85 the sleeves and being formed integrally with both. Sectional liners or wear plates 11 are inset in the outer sides of the flanges 9 and are secured in place by screws or the like 12 countersunk therein, said liners coöperating 90 with others 13 which are secured to the boxes 3 by countersunk screws or the like 14.

The inner ends of the sleeve sections 6 are provided with circumferential flanges 15 formed integrally therewith and similarly 95 joined at their ends to the flanges 7, said flanges 15 having circumferentially spaced openings 16 through which adjusting bolts 17 pass. Nuts 18 are threaded on the bolts 17 and bear against the outer sides of the flanges 15, so that by loosening the bolts 8 and adjusting the nuts 18, the two sleeves 6 may be forced outwardly along the axle 2 for the purpose of properly engaging their thrust bearings with the boxes 3, or rather 100 for moving the liners into proper engagement. When the necessary adjustment has been made, the nuts of the bolts 8 are again tightened so that the sleeves 5 are rigidly 105 clamped upon the axle and may not shift 110

thereon. Consequently these sleeves will serve not only to receive all side thrust of the locomotive, but will effectively reinforce the axle.

5 From the foregoing, taken into connection with the accompanying drawing, it will be obvious that although my invention is of extremely simple and inexpensive nature, it will be highly efficient and durable for the 10 purposes intended, particular emphasis being laid upon the little time and labor required for adjusting the sleeves to take up wear, or for totally removing these sleeves to apply new liners. Since probably the 15 best results are obtained from the exact details shown and described, these details are by preference employed, but within the scope of the invention as claimed, numerous minor changes may well be made.

20 **I claim:**

1. The combination with an axle, a pair of wheels rigid on the ends of said axle, and boxes for said axle at the inner sides of said wheels; of a pair of combined thrust and reinforcing sleeves secured around said axle and extending from the center thereof to said boxes, said sleeves having thrust bearings at their outer end abutting said boxes, and means between the inner ends of said

sleeves for spreading them to properly engage said thrust bearings with said boxes.

2. The combination with an axle, a pair of wheels rigid on the ends of said axle, and boxes for said axle at the inner sides of said wheels; of a pair of combined thrust and reinforcing sleeves around said axle and extending from its center to said boxes, each sleeve being formed of two semi-cylindrical sections having longitudinal flanges on their edges and circumferential flanges on their ends joined to the ends of said longitudinal flanges, the flange at the outer end of each sleeve forming a thrust bearing engaging the adjacent box and the inner flange of each sleeve having circumferentially spaced openings, adjusting bolts passing through said openings for forcing said thrust bearings into proper engagement with said boxes, and bolts securing said longitudinal flanges together to clamp the sleeves on the axle.

50 In testimony whereof I have hereunto set my hand in the presence of two subscribing witnesses.

JOHN C. LYONS.
